(57) **CLAIM**

The ornamental design for a white antenna, as shown and described.

DESCRIPTION

FIG. 1 is a front elevation view of a white antenna showing our new design, the claimed areas being white in color;

FIG. 2 is a top plan view thereof;

FIG. 3 is a bottom plan view thereof;

FIG. 4 is a side elevation view thereof;

FIG. 5 is a side elevation view thereof; and,

FIG. 6 is a front perspective view thereof.

The broken-line perimeter in FIG. 1 depicts a base that is not part of the claimed design. The other broken lines in FIGS. 1 and 6 depict small holes that are not part of the claimed design.

1 Claim, 1 Drawing Sheet**FIG. 1**

FIG. 2

FIG. 3

FIG. 4

FIG. 5

FIG. 6
